United States Patent

Des. 241,431
Patented Sept. 14, 1976

241,431

TRANSACTIONAL ANALYSIS TEACHING AID BOARD

Edward J. Johnson, Redondo Beach, Calif.
(7390 W. Manchester Ave., Los Angeles, Calif. 90045)

Filed June 17, 1974, Ser. No. 480,126

Term of patent 14 years

Int. Cl. D19—07

U.S. Cl. D19—59

Fig. 1.

FIG. 1 is a plan view of a transactional analysis teaching aid board showing my new design;

FIG. 2 is a view of the left side;

FIG. 3 is a view of the right side;

FIG. 4 is a view of the top edge; and

FIG. 5 is a view of the bottom edge thereof.

I claim:

The ornamental design for a transactional analysis teaching aid board, substantially as shown.
